JOHN STUART, OF SAUGATUCK, CONNECTICUT, ASSIGNOR TO CLARENCE WOOSTER, OF NEWARK, NEW JERSEY.

BUTTON.

1,105,110.

Specification of Letters Patent. Patented July 28, 1914.

Application filed October 16, 1908. Serial No. 457,989.

To all whom it may concern:

Be it known that I, JOHN STUART, a citizen of the United States, and a resident of Saugatuck, in the county of Fairfield and 5 State of Connecticut, have invented a certain new and useful Improvement in Buttons, of which the following is a full, clear, and exact description, reference being made to the accompanying drawings, forming 10 part of this specification.

This invention relates especially to improvements in the manufacture of buttons whose faces are cloth, except at the edges, which are rims of hard material encircling 15 the central cloth portions, the object of the invention being not only to simplify the manufacture of such buttons, but also to produce at low cost buttons having novel and pleasing characteristics.

20 The invention consists of a button comprising the parts hereinafter described and specified in the claims.

On the accompanying sheet of drawings, on which like reference-numerals designate 25 like parts in different views, Figure 1 is a top view of a shell that forms the back and rim of a button embodying the invention; Fig. 2, a face view of the button; Fig. 3, a top view of the body, which fits in the back 30 and whose face is cloth; Fig. 4, a partly sectional view of the button; Fig. 5, a top view of a shell that forms the back and of another button embodying the invention; Fig. 6, a top view of this button; Fig. 7, a top 35 view of the body or central portion thereof; and Fig. 8, a partly sectional view of this button.

The cloth faces of the central portions or 40 bodies of the buttons shown are alike and closely resemble the face of the central portion of a well known button which comprises a shell of vegetable-ivory that forms the back and rim of the button. The body and shell of that button are secured together by 45 means of a metal fastening which extends from the body through the shell and is clenched on the shell. The expense of performing the clenching operation, and the cost of the vegetable-ivory, are so much that 50 usually buttons like that can not be sold for use on garments for which cheap buttons are desired. This invention enables cheap buttons to be produced, having the form of buttons whose backs and rims are vegetable-

ivory, but differing therefrom more or less 55 in appearance, for the finish given to the shells of buttons embodying this invention is unlike that of vegetable-ivory shells, and may be greatly varied.

The shell shown in Fig. 1 may be formed 60 from a round blank of thin sheet material, which must have the proper resiliency to fit it to act as hereinafter explained. On the part 1 of this shell is an inwardly extending rim 2, and in the shell is a central 65 perforation 3. Preferably the shell is made of brass and the rim is formed by turning the edge 4 of the shell over and inward so that the shape of a cross-section of the rim is made as it is shown in Fig. 4. The body 5, 70 which fits in the shell, may be a common button, made as well-known cloth-faced buttons are usually made. Its diameter close to its face 6 is slightly greater than the internal diameter of the rim 2, and it comprises a tuft 7 formed to fit in and extend 75 through the perforation 3 in the shell, this tuft being a little longer preferably than that of a common button. The shell and body are made separately, the last operation 80 in making the button being that of putting the finished shell and body together. This consists merely in snapping them together with the fingers. The body is inserted in the shell and the edge of the body is pressed 85 through the rim 2, which yields and then springs back so that it covers the edge of the body and holds the latter in the shell the rim and shell being capable of enduring 90 stress great enough to change the internal diameter of the rim when this operation is performed. Not only is this operation very simple, but it does not affect the finish of the rim, so that it is feasible to finish the shells of buttons made as above described 95 in various ways and in different colors. The other button shown is composed of a resilient shell a central portion or body, and a metal eye. The shell 8 has an inwardly extending rim 9, like the rim of the shell 100 above described, and contains a slot through which a piece of wire extends that is bent so that it engages the shell and forms an eye 10 at the back of the shell. The body 11 is or may be cloth-covered and its diameter close to its face is slightly greater than the internal diameter of the rim 9. After 105 the body and shell have been made, the shell

having the eye attached to it and the desired finish having been imparted to the shell, they are snapped together with the fingers and thus the button shown in Figs. 5 6 and 8 is produced.

Having thus described my invention, what I claim as new and desire to secure by Letters Patent, is:

1. A button comprising a body, and a resilient shell formed from thin sheet-material and including an inwardly extending rim, the body fitting snugly between the back of the shell and inner side of the rim, and the shell being capable of enduring stress great enough to change the internal diameter of the rim when the body and shell are pressed together.

2. A button comprising the combination of a perforate resilient hollow part, and a body on which said hollow part fits and whose edge it covers, said hollow part including an inwardly extending rim behind which the edge of the body lies, and the resiliency of said hollow part being effective 25 to contract said rim over the edge of the

body, substantially as and for the purpose described.

3. A button comprising a body and a shell in which the body snugly fits, the shell surrounding and extending over and under the 30 edge of the body, and one of said parts including a resilient rim capable of enduring stress great enough to change some of its dimensions when the body and shell are forced together, the form of said rim in the 35 completed button being the same as it was before the body and shell were united.

4. A resilient button-shell made to fit on the body of a button, the shell being formed from thin sheet-material and including an 40 inwardly extending rim behind which the edge of the body lies, and the shell being capable of enduring stress great enough to change the internal diameter of the rim when the body and shell are pressed together. 45

JOHN STUART.

In presence of—

RUFUS WAKEMAN,

GEORGE E. WASHBURN.

Copies of this patent may be obtained for five cents each, by addressing the "Commissioner of Patents, Washington, D. C."

It is hereby certified that Letters Patent No. 1,105,110, granted July 28, 1914, upon the application of John Stuart, of Saugatuck, Connecticut, for an improvement in "Buttons," were erroneously issued to Clarence Wooster, as assignee of the entire interest in said invention, whereas said Letters Patent should have been issued to *the inventor, said Stuart and Clarence Wooster*, said Wooster being assignee of *one-half* interest only in said invention, as shown by the records of assignments in this office; and that the said Letters Patent should be read with this correction therein that the same may conform to the record of the case in the Patent Office.

Signed and sealed this 8th day of December, A. D., 1914.

[SEAL.]

J. T. NEWTON,
Acting Commissioner of Patents.
